JIG FOR MAKING CONTACT WITH THE ELECTRODES OF A DRY CONTACT RECTIFIER

Alec Hervey Bennett Walker and Leonard Alan Cole, King's Cross, London, England, assignors to Westinghouse Brake & Signal Company Limited, London, England

Application August 3, 1955, Serial No. 526,169

Claims priority, application Great Britain
September 13, 1954

7 Claims. (Cl. 219—19)

This invention relates to a jig of the kind which is suitable for making contact with the electrodes of a dry contact rectifier element, the contact being made in such a manner that heavy current may be passed through the element without damaging it.

A jig of the kind described may be used in putting into effect the method of manufacturing rectifier elements which is proposed in the co-pending application Serial No. 526,168, filed on August 3, 1955, by Alec Hervey Bennett Walker. In the specification of that co-pending application there is described a method of removing short circuits which are formed during the process of punching the elements from a large sheet upon which the rectifying layer and counterelectrode have previously been formed, the short circuits occurring as a result of the counterelectrode material being drawn across the edge of the element thereby producing thin trails which bridge the gap between the counterelectrode and the base plate at a number of places around the circumference of the element. In the method proposed the short circuits are removed, by applying a train of current pulses to the element in the forward direction such that the trails of counterelectrode material are volatilised without damage to the element.

According to the invention, a jig of the kind described comprises a first and a second metal block each having a contact surface, the contact surfaces being parallel to each other, the blocks being movable in a direction perpendicular to the contact surfaces, the first block being movable to a first or a second position and being subject to a biasing force which increases with the displacement of the block from said first position, the second block being manually movable to a first position and to a second position in which, when a rectifier element is positioned in the jig, the rectifier is gripped between the contact surfaces and said first block is held in its second position, the displacement of said first block then being such that the biasing force has a predetermined value.

Preferably the first metal block is spring biased and the biasing force is arranged to increase to the predetermined value by compression of the spring as the second block is moved from its first to its second position. In this way the pressure exerted upon a rectifier element positioned between the contact blocks may be arranged to increase steadily, thereby avoiding subjecting the rectifier element to a blow which might cause deformation when the contacts engage it.

Preferably also the contact surfaces of the blocks are of such a shape that when they engage the opposite faces of an axially aligned rectifier element the edges of the element project a short distance beyond the edges of the contact surfaces. These contact surfaces are conveniently arranged to be horizontal.

The blocks may be arranged to have a mass which is large by comparison with that of the element in order

2

to reduce the temperature rise of the element during the process of removing the short circuits.

If the rectifier element is placed with its counterelectrode adjacent the first block the contact surface 5 of the first block is preferably smooth and faced with a highly conducting metal such as silver the contact surface of the second block being roughened preferably by knurling, the second block being restrained from rotation and the first block being caused to rotate through 10 a small angle about an axis perpendicular to the contact surfaces as the blocks move from their first to their second positions. In this way the first contact block is caused to rub on the counterelectrode and a good contact is thereby assured.

15 The jig is preferably interlocked with a switch which controls the circuit supplying pulses of current, the interlock being such that no current can flow until the force exerted upon the rectifier element reaches a predetermined value that is, until the blocks are substantially 20 in their second position.

One embodiment of the invention, suitable for treating circular rectifier elements, will now be described, by way of example, with reference to the accompanying drawing. As shown in the drawing, the jig comprises 25 two cylindrical brass blocks 1, 2 axially aligned one above the other and having their adjacent end faces 3, 4 horizontal and parallel to each other. The end face 3 is covered with a thin layer of silver and the end face 4 is knurled. The upper block 1 is fixed to the lower end of a rod 5 which is axially aligned with the blocks, the upper portion of the rod sliding longitudinally in an insulating bushing 6 and carrying at its upper end a stop 7 which abuts against the upper end of the bushing 6 to limit the downward movement of the rod. A spring 8 arranged coaxially with the rod 5 abuts at its upper end against the lower surface of the bushing 6 and at its lower end against the upper surface of the upper contact block 1, the spring biasing the upper block towards its first or lower position. The lower block 2 is fixed to the upper end of a second rod 9 which is coaxially aligned with the first rod 5 and which slides longitudinally in a second insulating bushing 10. The insulating bushings 6 and 10 are fixed to a support 11. The block 2 is biased towards its first or lower position 30 by means of a spring 12 which abuts at its upper end against the lower surface of the bushing 10 and at its lower end against a stop 13 which is fixed to the rod 9. Downward movement of the block 2 is limited by the cam 14 upon which the lower end of the rod 9 rests. The cam 14 is fixed to a shaft 15 and is manually 35 rotatable through 180° by means of the knob 16, the angle of rotation being limited by means of the stop 17 which is fixed to the knob 16 and the two stops 18 which are fixed to the support 11. Also fixed to the shaft 15 is a second cam 19 which closes a limit switch 20 when the block 2 is in its high position. The switch 20 controls the operation of a supply circuit in such 40 a manner that the circuit of the kind shown in Figure 1 is energised to supply pulses of current to the blocks only when the block 2 is in its high position; when the block 2 is in its lower position the surfaces are separated from each other by a narrow gap.

The rod 5 is provided with a pin 22 which engages a cam slot 23 formed in the insulating bushing 6 and the 45 rod 9 is provided with a pin 24 which engages a cam slot 25 formed in the insulating bushing 10. The cam slot 23 lies at an angle to the axis of the rods 5 and 9 and the slot 25 lies parallel to this axis.

In operation, with the rod 9 in its lower position, a 50 rectifier element 21 to be treated is introduced into the narrow gap between the metal blocks and placed upon the lower block 2 with its counter-electrode uppermost.

The element, which is of a diameter slightly larger than that of the blocks 1, 2 is axially aligned with the blocks and the knob 16 is then operated to raise the lower block 2. After the upper surface of the element has abutted against the upper block further rotation of the knob 16 causes continued upward movement of the blocks 1, 2 until the spring 8 is sufficiently compressed to exert a force of four pounds weight on the upper block. As the blocks 1, 2 move upwards from their first or lower positions to their second or upper positions the pin 22 engaging the cam slot 23 causes the block 1 to rotate through an angle of approximately 20° and the pin 24 engaging the cam slot 25 prevents rotation of the block 2. Engagement of the knurled surface 4 of the block 2 with the base plate of the rectifier prevents rotation of the rectifier also. As the blocks move upwards, therefore, the surface 3 rubs against the counter electrode and the force exerted by the surface 3 upon the counterelectrode increases. In this way good electrical contact is assured. When the spring 8 is compressed to this degree the cam 19 operates the limit switch 20 which energizes the supply circuit, the circuit continuing to operate automatically in the manner indicated above to provide a train of ten pulses. At the end of the process the knob 16 is rotated to allow the rod 9 to move downwards, the switch 20 is open and the element removed.

When the rectifier element has a central hole the contact blocks are provided with central holes of slightly greater dimensions in order to allow the inner edge of the element to project inwards beyond the perimeter of the holes in the blocks. In this way the contact surfaces of the blocks are prevented from being contaminated by material evaporated from the edges of the element.

The biasing force of four pounds weight has been found to be satisfactory for rectifier element sizes ranging from 1 to 4 square centimeters in area.

Having thus described our invention what we claim is:

1. A jig of the kind described comprising a first and a second metal block by means of which contact is made to the two electrodes of a rectifier element, the blocks being axially aligned and each having a contact surface, the contact surfaces being parallel to each other, the blocks being movable in a direction perpendicular to the contact surfaces, the first blocks being movable to a first or a second position and being subject to a biasing force tending to move it towards said first position, said force increasing with the displacement of the block from said first position, the second block being movable from a first position to a second position in which, when the rectifier element is positioned in the jig, the element is gripped between the contact surfaces and said first block is held in its second position, the displacement of said first block then being such that the biasing force has a predetermined value.

2. A jig of the kind described comprising a first and a second metal block by means of which contact is made to the two electrodes of a rectifier element, the blocks being axially aligned and each having a contact surface, the blocks being movable in a direction perpendicular to the contact surfaces, the first block movable to a first or a second position and being subject to a biasing force tending to move it towards said first position, said force increasing with the displacement of the block from said first position, the second block being movable from a first position to a second position in which, when the rectifier element is positioned in the jig, the element is gripped between the contact surfaces and said first block is held in its second position, the displacement of said first block then being such that the biasing force has a predetermined value, the contact surface of one block being smooth and faced with a highly conducting metal, the contact surface of the other block being roughened, and means for rotating said one block through a small angle about an axis per-

pendicular to the contact surfaces as the blocks move from their first to their second position.

3. A jig of the kind described comprising a first and a second metal block by means of which contact is made to the two electrodes of a rectifier element, and an interlocking switch, the blocks being axially aligned and each having a contact surface, the contact surfaces being parallel to each other, the blocks being movable in a direction perpendicular to the contact surfaces, the first block being movable to a first or a second position and being subject to a biasing force tending to move it towards said first position, said force increasing with the displacement of the block from said first position, the second block being movable from a first position to a second position in which, when the rectifier element is positioned in the jig, the element is gripped between the contact surfaces and said first block is held in its second position, the displacement of said first block then being such that the biasing force has a predetermined value, and means to operate said interlocking switch to cause current to be supplied to the jig when the blocks are substantially in their second position.

4. A jig of the kind described comprising a first and second block by means of which contact is made to the two electrodes of a rectifier, the blocks being axially aligned and each having an opposing surface for engaging the rectifier electrodes, one of said block surfaces being smooth and faced with a highly conducting metal, the other of said block surfaces being roughened, the blocks being movable in a direction perpendicular to the contact surfaces, said first block being movable to a first or a second position, biasing means tending to move said first block to its first position, said second block being movable to a first or a second position, a second biasing means tending to move said second block to its first position, cam means for moving said second block to its second position, the rectifier being held between the contact surfaces of said blocks, said second block moving said first block against the biasing forces of both said resilient means to its second position, a second cam means associated with the one of said blocks for rotating said one block a limited degree as said one block is moved to its second position, and means for restraining rotation of the other of said blocks as said other block is moved to its second position.

5. A jig of the kind described comprising a first and second block by means of which contact is made to the two electrodes of a rectifier, the blocks being axially aligned and each having an opposing surface for engaging the rectifier electrodes, one of said block surfaces being smooth and faced with a highly conducting metal, the other of said block surfaces being roughened, the blocks being movable in a direction perpendicular to the contact surfaces, said first block being movable to a first or a second position, biasing means tending to move said first block to its first position, said second block being movable to a first or a second position, a second biasing means tending to move said second block to its first position, cam means for moving said second block to its second position, the rectifier being held between the contact surfaces of said blocks, said second block moving said first block against the biasing forces of both said resilient means to its second position, a first pin and slot connection associated with the one of said blocks for rotating said one block a limited degree as said one block is moved to its second position, and a second pin and slot connection for restraining rotation of the other of said blocks as said other block is moved to its second position.

6. A jig of the kind described comprising a first and second block by means of which contact is made to the two electrodes of a rectifier, the blocks being axially aligned and each having an opposing surface for engaging the rectifier electrodes, one of said block surfaces being smooth and faced with a highly conducting metal, the other of said block surfaces being roughened, the blocks being movable in a direction perpendicular to the contact surfaces, said first block being movable to a first

or a second position, biasing means tending to move said first block to its first position, said second block being movable to a first or a second position, a second biasing means tending to move said second block to its first position, cam means for moving said second block to its second position, the rectifier being held between the contact surfaces of said blocks, said second block moving said first block against the biasing forces of both said resilient means to its second position, a second cam means associated with the one of said blocks for rotating said one block a limited degree as said one block is moved to its second position, means for restraining rotation of the other of said blocks as said other block is moved to its second position, and a third cam means associated with said first cam means for actuating an electrical switch when both said blocks are moved to their second position.

7. A jig of the kind described comprising a first and second block by means of which contact is made to the two electrodes of a rectifier, the blocks being axially aligned and each having an opposing surface for engaging the rectifier electrodes, one of said block surfaces being smooth and faced with a highly conducting metal, the other of said block surfaces being roughened, the blocks being movable in a direction perpendicular to the contact surfaces, said first block being movable to a first or a sec- 20 25

5 10 15

ond position, biasing means tending to move said first block to its first position, said second block being movable to a first or a second position, a second biasing means tending to move said second block to its first position, cam means for moving said second block to its second position, the rectifier being held between the contact surfaces of said blocks, said second block moving said first block against the biasing forces of both said resilient means to its second position, a first pin and slot connection for restraining rotation of the other of said blocks as said other block is moved to its second position, and a second cam means associated with said first cam means for actuating an electrical switch when both said blocks are moved to their second position.
